DRY-CLEANING SOLVENT

Dwight L. Ebert, Chicago, Ill., assignor to Norris Products, Chicago, Ill., a partnership composed of Perry E. Norris and Dwight L. Ebert

No Drawing. Application October 14, 1940,
Serial No. 361,109

1 Claim. (Cl. 252—172)

My invention relates to the art of dry cleaning and particularly to a novel method of treating cleaning solvent to prepare the solvent for effective cleaning work.

There have been many theories about the effect of moisture introduced into dry cleaning solvents by means of absorbefacients and soap and the effect of the moisture in removing sweet-spots and water soluble soil not ordinarily effected by dry solvent. In one system the absorbefacient is introduced into the solvent first and water is then added to the solvent through a humidifier or mixing device. The solvent after the absorbefacient is added is stated to take up the water and form an optically clear solution. It is the use of this latter solution which is stated to remove sweet spots and water soluble soil in silks and woolens which are not ordinarily removed by immersion in dry solvent.

Solvent soluble dry cleaning soaps almost always contain moisture and it has often been claimed that the moisture in the soap goes into solution in the soapy solvent and that the soap and moisture content together have a cleaning action on water soluble spots.

No doubt the use of absorbefacients and soaps are effective in combination with various percentages of moisture in cleaning solvents and their use assists in removing water soluble spots and stains. I have found however that soil in fabrics is ordinarily not either of the water soluble kind or the solvent soluble kind but combinations of both and that if solvent is activated by moisture so that a detergent action is started then the cleaning action of the solvent continues.

I have further found that as long as moisture is present in cleaning solvent in an optically clear solution that a tremendously greater proportion of moisture is required to do effective cleaning work than if the solvent is activated by moisture, particularly in removing water soluble soil.

Absorbefacients and soaps all tend to cause moisture to go into solution in cleaning solvent. With substantially pure dry cleaning solvent such as standard Stoddard Solvent I have found that by homogenizing the moisture in the solvent in a fine cloudy mixture that even very low percentages of moisture such as .1%, based on the volume of the solvent, is effective in promoting an initial detergent action of the solvent which when once started will continue until the soil is substantially completely removed and that this action proceeds more effectively without the presence of an absorbefacient or dry cleaning soap.

though, if the dry cleaning soap is not of the solvent soluble kind, its effect is not ineffective.

To activate cleaning solvent I have found that moisture in the form of condensed dry steam may be effectively employed. As a specific example of one method of activating solvent, in a large dry cleaning plant I have found that by installing a steam separator on the steam line and introducing dry steam into a pipe in the pump circuit with which solvent in the washer is circulated that the solvent charge may be activated in a short period so that effective dry cleaning work can be done on silks and woolens soiled with so called water soluble soil.

15 The following specific directions will serve to teach a dry cleaner how to practice my invention.

Place a T in the pipe line leading into the washer. At the side opening of the T, place a reducing bushing to $\frac{1}{2}$ ", then a close nipple, an ordinary $\frac{1}{2}$ " steam valve, another nipple, a quick opening valve, then a nipple to which a steam separator is attached. The steam separator, of course, is hooked directly from the steam line, 20 and a trap leading to the return line. The steam circulates constantly through the separator and any steam passing through the valves will be so called dry. The purpose of two valves is to insure against steam leaks into the solvent when not wanted. This hook-up will be satisfactory for a 48 x 84 washer. Such a washer has a capacity of 175 gallons of solvent at the time when the steam is admitted. The procedure is as follows: 25 The load is first cleared on the filter, then by means of by-passing, the solvent is circulated by the filter through the pump and directly back into the washer, and this apparatus is connected into the line leading from the pump to the washer. After the break, dry steam is injected into the solvent for 15 seconds with both $\frac{1}{2}$ valves wide open. During this time the washer is revolving. Then after about 5 minutes the valves are changed so that the solvent is again pumped through the filter and allowed to clear up, after 30 35 40 45 which the load is finished.

A sample of the solvent after this 15 second injection contains from $\frac{1}{100}$ of 1% moisture to $\frac{1}{100}$ of 1%. A sample of the solvent after the injection of the moisture appears cloudy and milky and will remain so for from 12 to 24 hours.

50 The results obtained at a large dry cleaning plant in Chicago during several weeks continuous operation have been remarkably satisfactory. The dry cleaner and spotters who are handling the men's clothes on which most of the work has

been done state that they feel clean, linings are brighter, and that their spotting and washing is much reduced. This plant, which is one of Chicago's largest and lowest in price is of course interested in getting good work as cheaply and as quickly as possible. It had been their practice to sort out the pass-ups and then spot what they could, and then wash the bad ones. However, before washing the bad ones they would re-run them making what they would call an alky load. On this load they used alcohol, water, and soap.

The so-called fancy silks, consisting of ones that are painted, some loosely dyed, etc., which could not be run with a regular silk load without damage can be cleaned with my process, with much better cleaning and no bad results.

As one example of the use of my process the cleaner took a load of dresses which were put aside for washing, and made a steam run instead of a strong soap run. This time he varied the procedure by giving the solvent two injections of steam about 10 minutes apart, the first one being 15 seconds, and the second 10 seconds. This load seemed to be exceptionally good.

Unless the steam is so called dry, small droplets of water will condense in the solvent so that at all times it is preferable to use dry steam which forms a sufficiently fine cloudy precipitate as to be visible only in the form of a cloud and not in visible drops. It seems probable that as the steam is being injected and condenses in the

solvent that the solvent should be moving in fairly large volume.

I have found that solvent activated with about .1% of moisture forms an excellent hand spotter, for removing spots from light fabrics and felt, such as felt hats. In removing spots from garments with a dry solvent there is normally a tendency to form stain rings around the spot but with my activated solvent such rings appear to be avoided.

While my activated solvent is particularly effective for dry cleaning I have also found that hydrocarbon fuels can be activated with moisture in a similar manner and that such fuels tend to form less carbon in internal combustion motors and the operation is quieter.

Having thus described my invention, what I claim as new and desire to secure by Letters Patent is:

A method of activating dry cleaning solvent of the class represented by Stoddard solvent for effective use in removing water soluble soil in dry cleaning which consists in distributing moisture by the injection of substantially dry steam into the solvent in a percentage of substantially .1% based on the volume of the solvent and in a sufficiently finely divided condition as not to substantially precipitate out on twelve hours standing.
